DRIER APPARATUS

Edgar L. Zehrbach, Mansfield, Ohio, assignor to
Westinghouse Electric Corporation, East Pitts-
burgh, Pa., a corporation of Pennsylvania

Application December 6, 1949, Serial No. 131,447

4 Claims. (Cl. 34—82)

1

My invention relates to apparatus for drying fabrics or the like and, particularly, to domestic type clothes drying apparatus. An object of my invention is to provide improved apparatus of this kind.

Many clothes driers of the domestic type are installed in laundries or other rooms and discharge air employed for drying directly into the room in which they are located. During operation, lint which clings to the clothes is separated therefrom and is carried in suspension in the air discharged from the drier. A lint trap of foraminous construction is usually removably carried by the drier structure for the separation of the lint from the discharged air. For the sake of appearance and because of space limitations, such traps are small and, therefore, require frequent cleaning. Many operators are negligent in this respect with the result that the traps become clogged with lint and interfere with the discharge of air from the drier. For best results, the trap should be cleaned after each operation of the machine.

In accordance with my invention, means is provided for indicating to the operator that the trap should be cleaned, which means is activated in response to the opening of the door of the drier for the removal of the dried fabrics.

Preferably, the trap structure is actuated to a position on the drier where it will be visible to the operator each time the door of the drier is moved to its full open position for the removal of the fabrics from the drier. In the active or operating position of the trap, it is out of view on a side wall of the drier for the sake of appearance. When the door is opened, the trap is moved, automatically, to a position wherein it partially extends above the top wall of the drier casing. Accordingly, the operator is warned that the trap should be cleaned. Some notification to this effect may be printed or stamped on the trap. The arrangement is such that the door may be partially opened for adding a garment to the drier or for inspecting the load without actuating the trap, as described, to the warning position thereof above the wall of the casing.

A further object of my invention is to provide an improved domestic clothes drier having provisions for warning the operator that the trap should be cleaned each time the drier is operated.

A still further object of the invention is to actuate the lint trap of a drier to a warning position on the drier in response to movement of the door of the drier to open position.

2

These and other objects are effected by my invention as will be apparent from the following description and claims taken in connection with the accompanying drawings, forming a part of this application, in which:

Fig. 1 is a front elevation of a domestic clothes drier constructed and arranged in accordance with my invention, portions of the outer casing being broken away;

Fig. 2 is a vertical sectional view taken through the casing of the drier with a portion of the casing being shown in elevation;

Fig. 3 is a rear elevation of a portion of the casing and illustrating the lint trap carried thereby;

Fig. 4 is a section taken along the line IV—IV of Fig. 3;

Fig. 5 is a front elevation of a portion of the casing and showing the upper end of the lint trap in a different position on the casing; and

Fig. 6 is an enlarged section of a latch structure shown in Fig. 4.

Reference will now be had to the drawing wherein I have elected to disclose my invention applied to a domestic type clothes drier having an outer casing structure generally indicated at 10 and including a rear wall 11 and a front wall 12, an upper portion 13 of the latter being inclined rearwardly and upwardly of the casing structure 10. Arranged within the casing structure 10 is a generally cylindrical baffle 14 which defines and encloses a drying chamber 15 within the casing. The baffle 14 has the rear end thereof welded or otherwise secured to the rear wall 11 of the casing and the front end of the baffle 14 is connected to the front wall portion 13 of the casing by a chute 16 which, as shown, diverges from the outer casing toward the baffle 14. The outer end of the chute 16 is secured in any well understood manner to the front wall of the casing and the inner end of the chute 16 is welded or otherwise secured, as shown at 17, to the front end of the baffle 14. The open front end of the chute is closed by a door 18 having a pair of supporting brackets 19 which are hinged on bolts 21, the latter being carried by the front wall 12 of the casing in any well understood manner.

Arranged within the drying chamber 15 is a basket generally indicated at 22 and including a cylindrical side wall 23 which is perforate, substantially, throughout its extent, a number of the perforations being indicated at 24. The basket 22 is also provided with a plurality of radially, inwardly extending vanes 25 which

3

function to tumble the fabrics during rotation of the basket. The front end wall of the basket, indicated at 26, is provided with a relatively large access opening 27 which registers with the inner end of the chute 16. A rear wall 28 of the basket is secured in any well understood manner to a shaft 29, the latter being journaled in a suitable bearing 31 carried by the rear wall 11 of the casing.

Rotation of the basket is effected in any conventional manner by an electric motor 32 mounted in a lower portion of the casing 12 and having a shaft 33. The shafts 29 and 33 may be connected by a suitable belted transmission generally indicated at 34 and including a driving pulley 35 and a driven pulley 36. It will be noted that intermediate driving and driven pulleys may be employed for providing the speed reduction required, but these have not been shown for the sake of brevity and clearness.

The motor 32 also functions to drive a blower, the rotor of which is indicated at 37 and keyed or otherwise secured to the shaft 33. The rotor 37 of the blower operates within a blower casing 38 which is formed at one end of a duct structure 39, the latter extending transversely of the casing and supporting, in part, the cylindrical baffle 14. During operation of the motor, air enters the casing structure 10 from the ambient atmosphere through a plurality of openings 41 and enters the blower casing 38 through a relatively large inlet opening 42. The air is passed through the duct structure 39 and is heated by an electric heater 43. The latter is preferably formed of bare resistance wire and supported in any understood manner by a plate 44 which functions to close a service opening 45 formed in the front wall of the duct 39.

Heated air passes from the duct structure 39 through a conduit 46 to the chute 16 and thence through the access opening 27 of the basket into contact with fabrics which are elevated and dropped by the basket during its rotation. The heated air abstracts moisture from the fabrics and is discharged from the drying chamber 15 into a box structure 47 carried in the upper right hand side of the casing 10, as shown in Figs. 1 and 2. The rear wall 11 is provided with a discharge opening, indicated at 48 and best shown in Fig. 4, for the passage of air and moisture from the box 47 to the ambient atmosphere. A drier having air circulating features of the type described up to now is disclosed and claimed in the copending application of Ray T. Wakefield, Serial No. 127,454 filed November 15, 1949, and assigned to the assignee of the present application.

In the operation of a drier of the type disclosed, lint which clings to the fabrics is dislodged therefrom during their tumbling in the basket and is carried in suspension in the air which is passed through the discharge opening 48. In order to separate the lint from the air, a lint trap generally indicated at 51 is supported by the rear wall 11 of the casing and over the discharge opening 48 therein. While any suitable lint trap may be employed, I prefer to show one of the type disclosed and claimed in my copending application, Serial No. 794,843, filed December 31, 1947, and assigned to the assignee of the present application. For the sake of appearance and because of space limitations, the lint trap structure 51 is made relatively narrow and is carried in an inconspicuous place on the rear wall of the drier.

4

The lint trap 51 includes a shallow pan 52 which is flanged as shown at 53. The upper portion of the pan 52, as best shown in Figs. 3 and 4, or the portion directly opposite the opening 48 is imperforate. The lower portion of the pan 52 is provided with a relatively large air discharge opening 54 which is provided with a screen 55 for the separation of lint from the air passed through the opening 54. The lint trap 51 is positioned on the rear wall 11 of the casing by a pair of guides 56 under which the flanges 53 are disposed. In order to provide a substantially airtight connection between the lint trap 51 and the casing wall 11, the latter is provided with a flange 57 substantially coextensive with the flange 53 and engageable thereby in the operating position of the trap 51. The flange 57 is formed on a frame 58 which is welded or otherwise secured to the rear wall 11 of the casing. A handle 59 is provided for lifting the lint trap 51 when it is to be removed for cleaning. In this connection, the lint trap 51 is lifted until the flange 53 is clear of the guides 56 after which the lint trap 51 is free and may be readily removed and cleaned, it being noted that one entire side of the lint trap structure is open in order to provide access to all interior surfaces of the lint trap.

During operation of the drier, lint suspended in the air passing through the screen 55 is collected thereon. It is desirable that this lint be regularly removed from the trap and, in fact, it is desirable to remove this lint after each operation of the drier in order to insure that the flow of air from the drier will never become impeded. As set forth heretofore, many operators are negligent in cleaning the trap. In accordance with my invention, a signaling device is employed which will notify the operator at the end of each cycle of operation that the lint trap should be cleaned. Any well known form of signaling device may be employed and operated by the door 18 of the drier when it is lowered to its open position for the removal of dried fabrics from the drier. Preferably, the lint trap itself is employed as a signaling device, the arrangement being such that the lint trap structure 51 is raised from its operating position, as shown in Fig. 3, to a signaling or notifying position, as shown in Fig. 5, when the door 18 is open. A legend 61 may be printed or stamped on the inner surface of the lint trap pan 52 for notifying the operator that the trap should be cleaned.

As shown in Figs. 1 to 3, inclusive, the pan 52 of the trap is biased upwardly to the position thereof shown in Fig. 5 by a leaf spring 62 riveted or otherwise secured to the rear wall 11 of the casing. The pan 52 is retained in its operating position by a latch structure generally indicated at 63, as best shown in Fig. 6. This latch structure 63 includes a resilient spring latch 64 which is secured to the pan 52 by bolts 65. The latch 64 has an opening 66 formed therein for receiving catches 67, the latter being formed on a plate 68 which is positioned on the rear wall 11 of the casing. As shown, the plate 68 is secured to the frame 58 by a stud 69 extending through openings in the plate 68 and frame 58 and having a spun-over end, as shown at 71.

The release of the latch 64 from the catch 67 is effected by a wire 72 which extends through an opening formed in the stud 69. As best shown in Figs. 1 and 2, the wire 72 extends forwardly through the casing from the latch structure 63 and thence downwardly adjacent the inner face

of the front wall portion 13 of the casing. The lower end of the wire extends through an opening 73 in one of the door brackets 19 and the end of the wire is bent to prevent its dislodgement from the opening 73, as shown at 74. The upper portion of the wire 72 is positioned by a pair of fingers 75 formed on the inner side of the front wall portion 13, between which the wire is disposed. It will be understood that the wire 72 is relatively stiff and, preferably, formed of spring steel.

When the drier is in operation for the drying of fabrics, the door 18 is closed or in the position shown in Figs. 1 and 2. The lint trap is also positioned as shown in these two figures as well as Figs. 3 and 4. At the conclusion of the drying operation, the door is swung through approximately 120 degrees to a horizontal position from the position shown in Fig. 2. Accordingly, that portion of the wire 72 which is adjacent the wall portion 13 of the casing is swung upwardly between the positioning fingers 75. This movement of the wire forces the horizontal portion of the wire 72 rearwardly and into engagement with the latch 64. Fig. 6 shows a portion of the wire 72 as the door is being moved downwardly and just prior to the releasing of the latch 64 from beneath the catches 67. When the door is moved to its horizontal position, the wire will have forced the latch out of engagement with the catch 67 and the spring 62 will then move the lint trap from the position shown, for example, in Fig. 3 upwardly to the position shown in Fig. 5. In the latter position, the upper end of the trap is raised to an exposed position above the top of the drier casing for notifying the operator that the trap should be cleaned.

In this notifying position, the trap 51 is still positioned by the guides 56. The operator may then lift the trap from the casing for cleaning. In assembling the lint trap 51 to the casing, the operator positions the trap behind the upper end of the guides 56 and then forces the trap structure downwardly. In doing so, the latch 64 rides over the inclined upper surfaces of the catches 67 and then snaps beneath the catches 67, the latter being received in the opening 66 in the latch. The arrangement is such that the trap is unlatched at about the time the door is moved to its horizontal position. Accordingly, the operator may partially open the door for the insertion of a fabric into the basket after the latter is in operation or for an inspection of the load in the basket without tripping the latch.

From the foregoing description, it will be apparent that I have provided an improved drier having provisions for notifying the operator that the lint trap requires attention, the notifying or signaling means being actuated in response to movement of the drier door to its full open position. The lint trap itself is preferably employed for this signaling operation and is actuated to a position wherein it is unlatched from the drier casing in carrying out the operation. Accordingly, the trap is readily removable for cleaning. The arrangement is such that the door may be partially opened for an inspection of the load at any time or for adding a garment or two to the drier after it has been started.

While I have shown my invention in but one form, it will be obvious to those skilled in the art that it is not so limited, but is susceptible of various changes and modifications without departing from the spirit thereof.

What I claim is:

1. In a drier for fabrics, the combination of a casing structure having a drying chamber formed therein and provided with an access opening in a wall thereof, a door carried by the casing structure and closing said access opening, said door being movable to an open position, means for conveying air to the drying chamber for the abstraction of water from fabrics contained therein, means defining a passage in the casing for the discharge of air and suspended lint from the drying chamber, a lint trap, means arranged on the exterior of the casing for supporting the lint trap and providing for movement thereof between an active position and a warning position, means for moving the lint trap to its warning position and means for energizing said trap moving means in response to movement of said door to its open position.
2. In a drier for fabrics, the combination of a casing structure having a drying chamber formed therein and provided with an access opening in a wall thereof, a door carried by the casing structure and closing said access opening, said door being movable to an open position, means for conveying air to the drying chamber for the abstraction of water from fabrics contained therein, means defining a passage in the casing for the discharge of damp air and lint suspended therein from the drying chamber, a lint trap, means arranged on the exterior of the casing for supporting the lint trap and providing for movement thereof between an active and a warning position, means biasing the lint trap to its warning position, a latch for retaining the lint trap in its active position and means connecting said door and said latch for releasing the latch in response to movement of the door to its open position.
3. In a drier for fabrics, the combination of a casing structure having a drying chamber formed therein and provided with an access opening in a wall thereof, a door carried by the casing structure and closing said access opening, said door being movable to an open position, means for conveying air to the drying chamber for the abstraction of water from fabrics contained therein, means defining a passage in the casing for the discharge of damp air and lint suspended therein from the drying chamber, a lint trap, a pair of guides arranged on the casing for removably supporting said lint trap, said lint trap having means engaging the guides and providing for vertical movement of the trap on the guides, a spring biasing said lint trap upwardly from its operating position to a second position wherein at least a portion of the trap extends above the casing while supported by the guides, latching means for maintaining the trap in its operating position and means responsive to movement of the door to its open position for releasing the latching means.
4. In a drier for fabrics, the combination of a casing structure having a drying chamber formed therein and provided with an access opening in a wall thereof, a door carried by the casing structure and closing said access opening, said door being movable to an open position, means for conveying air to the drying chamber for the abstraction of water from fabrics contained therein, means defining a passage in the casing for the discharge of damp air and lint suspended therein from the drying chamber, a foraminous trap structure covering said passage for separating lint from the air, means for movably supporting said trap on a side of the casing structure below the top thereof and providing for removal of the

trap from the casing, a spring biasing said trap structure to a position wherein it partially extends above the top of the casing, a latch for retaining the trap structure in its operating position and a wire disposed within the casing and connecting said door and latch, said wire actuating the latch for the release of the trap structure in response to movement of the door to its open position.

EDGAR L. ZEHRBACH.
